UNITED STATES PATENT OFFICE.

HARRY SIROT, OF NEW YORK, N. Y.

DRAFTSMAN'S PARALLEL-LINE INSTRUMENT.

Application filed April 18, 1922. Serial No. 555,108.

To all whom it may concern:

Be it known that I, HARRY SIROT, a citizen of the United States, residing at New York, in the county of the Bronx and State of New York, have invented certain new and useful Improvements in Draftsmen's Parallel-Line Instruments, of which the following is a specification.

This invention relates to parallel line instruments particularly used in general engineering practise, the main object being the provision of an instrument which can be removably secured at any location on a drawing board and will permit a series of straight parallel lines to be drawn parallel and adjacent to a guide line, without the necessity of shifting or employing other instruments.

Another object is the provision of a device as described which essentially comprises a so-called straight edge having a triangle movable thereon so that the latter can be set to jibe with irregular angles and transpose the latter from a drawing to an article of manufacture or vice versa.

These and other objects will become apparent in the description below in which characters of reference refer to the like-named parts in the drawing.

Referring briefly to the drawing, Figure 1 is a front elevational view of the device showing the triangle thereon in various positions.

Figure 2 is an end elevational view of the same.

Figure 3 is a fragmentary front elevational view showing the triangle in tilted position.

Figure 4 is a partial cross sectional view thru the device taken on line 4—4 of Figure 1.

Figure 5 is a bottom plan view of Figure 3.

Describing the drawing in detail, the numeral 10 indicates a rectangular bar, commonly called a straight edge, having inclined surfaces 11 upon which graduations 12 corresponding to inch measurements are formed. Said bar 10 is provided with a channel 13 extending thruout its length the central portion thereof being enlarged into 50 a semi-circular recess 14.

A triangle 15 provided with an opening 16 has a plurality of finger notches 17 formed on the edges of said opening by which the triangle can be lifted from the 55 surface it is placed on. Said triangle has slots 18 and 18^a extending parallel to corre-

sponding sides which are joined to each other at their point of intersection 19 located near one of the vertices.

A lug 20 located centrally on the upper 60 surface of bar 10 has a hole therein which loosely receives a stem 21 threaded at the end 22 and provided with a bend 23 at its opposite end. Said bend extends downwardly into bar 10 thru an enlarged hole 24 65 and is adapted to engage either of the said slots 18 or 18^a.

A thumb screw 25 engaging the threaded end 22 of member 21 shoulders on the side of lug 20 and provides a means for locking 70 the triangle in any position on the bar 10. Thumb tacks 26 secured in the ends of the bar 10 project from the bottom surface and provide a means for holding the instrument in place on a drawing board or other similar 75 surface.

The instrument, when in use, is placed upon the drawing board in a position where it is desired to rule or draw a series of parallel lines. The bar is firmly pressed downward so that the tack points 26 are embedded in the board. By moving the triangle in either direction a series of lines can be drawn parallel to each other. These lines are widely used in a drafting room 85 when indicating sections and is termed cross hatching.

The instrument can also be used by mechanics or carpenters as a means for transposing an angle from one piece of work to 90 another.

In Figure 1 the triangle is indicated in two positions in which the full lines indicate it in position for angular parallel lines while the broken lines show one of its sides 95 in perpendicular alignment. The change is accomplished by sliding the triangle to the intersection 19 and tilting it or rotating it about said intersection. Figure 3 shows the triangle being rotated about said intersection. Member 23 engaging either of the slots 18 and 18^a can secure the triangle in any of its positions by manipulation of the thumb nut 25.

I claim:

1. A device of the class described comprising a bar having a channel formed therein, a triangle slidable in said channel, tacks projecting from said bar and adapted to removably secure the latter in place, and means for securely locking said triangle in 110 any position relative to said channel.

2. A device of the class described comprising a bar having a channel formed therein, a triangle slidable in said channel and having inter-communicating slots formed therein, means engaging said slots for locking said triangle in any position on said bar and means for securing said bar to a drawing board.

3. A device of the class described comprising a bar having a channel formed therein, a lug formed centrally on said bar, a threaded stem slidable therein and having a downwardly bent portion at one end, a thumb nut

engaging said threaded stem, a triangle slidable in said channel having inter-communicating slots arranged parallel to its corresponding sides and adapted to receive the downwardly bent portion of said stem, said thumb nut adapted to securely lock the triangle in a desired position on said bar, said triangle being rotatable on said bent portions when said thumb nut is in unlocked position and means for securing said device in place on a drawing board or the like.

In witness whereof I, affix my signature. 25

HARRY SIROT.
